UNITED STATES PATENT OFFICE.

HENRY MORTIMER HERRING, OF NORTH ATTLEBOROUGH, MASSACHUSETTS,
ASSIGNOR TO FRED S. GILBERT, OF SAME PLACE.

CHECKREIN-FASTENER.

SPECIFICATION forming part of Letters Patent No. 571,830, dated November 24, 1896.

Application filed August 8, 1896. Serial No. 602,163. (No model.)

To all whom it may concern:

Be it known that I, HENRY MORTIMER HERRING, a citizen of the United States, residing at North Attleborough, in the county of Bristol and State of Massachusetts, have invented 5 certain new and useful Improvements in Checkrein-Fasteners, of which the following is a specification, reference being had therein to the accompanying drawings.

10 My invention relates to an improved device for holding the checkrein firmly upon the check-hook in order to prevent its accidental displacement by the horse in throwing his head around.

15 The invention is illustrated in the accompanying drawings, in which—

Figure 1 is an elevation showing the device attached to a checkrein and hooked over the check-hook. Fig. 2 is a perspective view of 20 the device detached from the check rein and hook.

The device consists, essentially, of a loop or fastener A, designed to hook over the check-hook, with means whereby it is secured to the 25 end of the checkrein. The part A is preferably formed of one piece of wire of suitable spring metal having a bent forward portion a, adapted to hook over the check-hook, and the sides a' diverging slightly. The ends of 30 these side portions a' are bent around to extend forwardly, the extreme forward ends of the wire diverging and terminating in proximity to the bend a, as shown at a²a'. These spring ends a² are so arranged in relation to 35 each other and the forward portion of the loop that they are forced apart by the check-hook when the loop is slipped over it, and the spring action of the ends or arms a² tends to hold the check-hook clamped firmly between 40 the bend a and the said arms, thus preventing it from being accidentally displaced or thrown out. The friction of the parts under

the spring action also prevents any rattling of the parts one upon the other.

Suitable means are provided for securing 45 the fastener to the checkrein, this means consisting, preferably, of an endless loop of wire B, doubled upon itself and forming eyes or recesses b, which engage the rear bends of the sides a', while the wire between these 50 portions b extends laterally straight across, forming a portion b', adapted to receive the loop of the checkrein.

Having thus described my invention, what I claim is—

1. A checkrein-fastener, comprising a loop with means for securing the same to the checkrein, the ends of said loop being free and adapted to have frictional contact with the check-hook, substantially as described. 55

2. A checkrein - fastener comprising the loop adapted to engage the check-hook, said loop being formed of a single piece of wire having the ends doubled upon the sides and forming spring clamping-arms adapted to 60 bear against the check-hook, and means for securing the fastener to the checkrein, substantially as described. 65

3. A checkrein - fastener comprising the loop adapted to engage the checkrein, said 70 loop being formed of a single piece of wire having the ends doubled upon the sides and forming diverging spring-arms adapted to embrace the check-hook, and the wire loop doubled upon itself to form eyes, said eyes 75 engaging the bends of the fastener between the main portion and the spring-arms, substantially as described.

In testimony whereof I affix my signature in presence of two witnesses.

HENRY MORTIMER HERRING.

Witnesses:

WILLIAM H. POND,
EDW. E. KING.
